COMBINED SEAT AND BACK REST UNIT

Earl H. Koepke, Sturgis, Mich., assignor to
Harter Corporation, Sturgis, Mich.

Filed Dec. 13, 1972, Ser. No. 314,606

Term of patent 14 years

Int. Cl. D6—06
U.S. Cl. D6—197

FIG. 1

FIG. 2

FIG. 3

FIG. 1 is a top view of a combined seat and backrest unit according to the invention;

FIG. 2 is a side perspective view of a combined seat and backrest unit according to the invention; and

FIG. 3 is a front side perspective view of a combined seat and backrest unit according to the invention.

The undisclosed portion of the back rest is plain and unornamented.

I claim:

The ornamental design for a combined seat and backrest unit, substantially as shown and described.
